UNITED STATES PATENT OFFICE.

GUSTAV BUCKY, OF BERLIN, GERMANY, ASSIGNOR TO SIEMENS & HALSKE, A. G., OF SIEMENSSTADT, NEAR BERLIN, GERMANY, A CORPORATION OF GERMANY.

APPARATUS FOR THERAPEUTICALLY APPLYING DIATHERMIC CURRENTS.

1,293,689.

Specification of Letters Patent. Patented Feb. 11, 1919.

Application filed June 4, 1914. Serial No. 842,926.

To all whom it may concern:

Be it known that I, GUSTAV BUCKY, a German citizen, and resident of Berlin, Germany, have invented certain new and useful 5 Improvements in an Apparatus for Therapeutically Applying Diathermic Currents, of which the following is a specification.

The present application relates to an apparatus for diathermic treatment, that is to 10 say for an electro-medical treatment in which high frequency alternating currents of very high tension are passed through the body of the patient by the electrodes which are applied directly to the body for producing 15 heating effects. Such high frequency alternating currents directly applied by means of electrodes to the human body for thermo-penetration are called in electro-medicine "diathermic currents."

20 The high frequency currents may be produced in any suitable manner.

In the therapeutic application of diathermic currents according to the heretofore used method a discomfort is felt by the patient in that at some places of the contacting surfaces of the electrodes a relatively large amount of heat is developed which will cause itching or burning. The reason for this is found in the fact that some narrow 25 parts of the body possess a much better conductivity than the parts surrounding the same and that in consequence thereof an uneven distribution of the current lines issuing from the electrodes and consequently of the 30 developed heat will be produced.

According to my present invention this impermissible heating at the electrodes is prevented by having the diathermic current periodically and at regulable times greatly 40 weakened or entirely interrupted and by having the same again switched on at normal current strength for a time which is also regulable. In this manner the ratio between the intermissions or the duration of the small 45 load and the duration of the closure of the current at normal current strength is so chosen that the electrodes will cool off during the time of intermission and therewith prevent temperatures which will cause a disagreeable sensation of burning.

50 By my present invention the therapeutic action of the diathermic currents upon the human body will not be disturbed, since the temperature of the body in distinction from that of the electrodes will practically not

change at all on account of the poor heat conductivity of the skin during the times of intermission. It will therefore also be possible to generate greater amounts of heat than heretofore, without causing a combustion of the skin. 60

For carrying the afore-pointed-out method into effect devices of various kinds may be employed. If the load shall take place alternately with large and small current strength, 65 resistances or choke coils may be switched on and off, or also the coupling between primary and secondary circuit may be changed periodically by rhythmically moving to and fro one of the two coupling coils relatively to 70 the other, whereby the variation of the current strength may be accomplished either gradually or suddenly.

In case the present method is employed in such a manner that the diathermic current 75 is alternately fully switched on and off, interrupters of various construction may be used, such as are known for various purposes, where the duration of make and break of the current is made regulable within large 80 limits.

In the accompanying drawing Figure 1 is a diagram showing the apparatus for treating an organ of the body with diathermic currents of regulable character according to this invention, and Fig. 2 a modified form 85 of the apparatus of Fig. 1 for simultaneously treating two different parts of the body with diathermic currents of desired character.

In Fig. 1 I have shown a Leduc interrupter comprising two brushes *b*, and a disk *s* consisting of insulating material *i* and carrying a number of metal segments *m* which are separated from each other and distributed over the periphery of said disk. 95 The disk may be driven by hand or by means of a motor for interrupting the contact between said brushes *b* in dependence of its speed of rotation. The two brushes *b* are interposed in the primary circuit of the transformer *t*, so that upon rotation of the switch *s* this circuit will be alternately closed and interrupted. Furthermore one of the two brushes *b* can be adjusted relatively to the other according to the scale *sc*, so that 100 in this manner the duration of the make and break of the current can be varied as desired. The secondary circuit of the transformer *t* includes a spark gap *f* which is connected across the terminals of the second- 105 110

ary winding of the transformer t , and condensers c and a coupling coil k_1 which are connected in series with said secondary circuit as shown in the drawing, thus representing an oscillating circuit. A second coupling coil k_2 is connected in series with further condensers c and the electrodes e which are contacting with the part of the body p to be treated, all as represented in the drawing. Accordingly, current will be intermittently conveyed to the body p , whereby the periods of current supply and interruption may be so regulated by means of the position of the one brush b , that no impermissible heating takes place at the electrodes. Furthermore by regulating the speed of rotation of the disk s the absolute duration of the flow and the intermission of current may be adjusted. Instead of the type of interrupter shown in the drawing evidently other kinds of interrupters may be employed.

It is especially important to change the ratio between the duration of current flow and the intermissions thereof, in case it is desired to simultaneously treat a plurality of parts of the body having different thicknesses by different oscillating circuits, so that one and the same uniformly applied current strength would cause a different heating of the body.

Fig. 2 shows an arrangement of this kind, whereby the two circuits serving for heating the body are in operation one after the other and for the purpose of avoiding the feeling of "faradic touch" during the operation of switching the secondary coil upon the two electrode circuits, the primary circuit of the transformer feeding the oscillating circuit is switched off immediately before said switching operation and again connected after completed switching operation. For this purpose I employ two disks s_1 and s_2 similar to the disk s of Fig. 1 and carrying at opposite places on their periphery the metal segments m_1 and m_2 . On the periphery of each disk slide a pair of brushes b_1 , b_2 and b_3 , b_4 which are included in the primary circuit of the transformer t supplying the circuit of the diathermic currents, so that each pair of brushes will be enabled to close the circuits. The adjustment of the length of the arc between the brushes that is of the brush distance, can be accomplished by adjusting the brushes b_1 and b_3 according to the scales sc_1 and sc_2 . The metal segments and the brushes b_1 , b_2 , b_3 , b_4 are so arranged that at no time are both circuits simultaneously closed. The disks s_1 and s_2 are mounted upon a common axle w which may be driven by a hand wheel h or by means of a motor, said axle carrying furthermore two brushes d which are insulated from each other and which are connected over slip rings r and over condensers c with the sec-

ondary coil k_2 , the primary coil k_1 being fed by the transformer t similarly to the arrangement described in Fig. 1.

The latter pair of brushes d slide on the outer part of the periphery of the stationary disk o , over its metal segments n , of which each diametrical pair is connected to a pair of electrodes e_1 and e_2 respectively, so that upon rotation of the brushes b the organs p_1 and p_2 interposed between these pairs of electrodes will be alternately traversed by diathermic current which will cause heat to be developed at the places of contact. The length of the several segments n , m_1 and m_2 and their position relatively to the brushes is so chosen that switching off and on of the primary current will take place before and after the respective switching operation for the secondary circuit on either of the electrode circuits.

In this manner every sensation of "faradic touch" will be avoided for the patient when switching over the circuits of the diathermic currents, and by adjusting the brushes b_1 and b_3 the duration of the make and the break of the current in the two electrode circuits may be adjusted independently from each other.

With the device described therefore by a faster or slower rotation of the disks s_1 and s_2 and the brushes d which may be accomplished by means of the handle h or motor as desired and by adjusting the brushes two features may be attained: firstly, at the contacting surface of the electrodes no impermissibly high heating of the body will be produced, and secondly, the amounts of heat developed in either simultaneously treated part of the body can be regulated independently from each other.

Having thus described in the foregoing some embodiments of my invention, I do not wish to be understood as limiting myself to the precise constructions as shown, since modifications may be made thereon without departing from the principle or sacrificing any of the advantages of this invention.

I therefore claim as new and desire to secure by Letters Patent of the United States:—

1. Apparatus for therapeutically applying diathermic currents, comprising means for producing high frequency alternating currents of high tension, metallic electrodes connected in circuit with such current-producing means and adapted to be placed directly upon the human body, and means for periodically varying the current applied to the body at sufficient time intervals to permit cooling of said electrodes and the contact surface of the body.

2. Apparatus of the type described, comprising a primary high frequency circuit adapted to be excited from a source of commercial alternating current, a secondary

high frequency circuit coupled with the primary circuit, metallic electrodes connected with said secondary circuit and adapted to be placed directly upon the human body, 5 means for periodically varying the current applied to the body, and regulating means for adjusting the times of action of the former means.

3. Apparatus of the type described, comprising a primary high frequency circuit adapted to be excited from a source of commercial alternating current, a secondary high frequency circuit coupled with the primary circuit, metallic electrodes connected 10 with said secondary circuit and adapted to be placed directly upon the human body, means for periodically interrupting the current applied to the body, and regulating means for adjusting the time of action of 15 the former means.

4. Apparatus of the type described, comprising a low frequency circuit adapted to be connected to a source of commercial alternating current, means for periodically interrupting this circuit, regulating means 20 for adjusting the times of action of the former means, a high frequency primary circuit excited from said low frequency circuit, a secondary high frequency circuit, coupled 25 with the primary circuit and metallic electrodes connected with said secondary circuit and adapted to be placed directly upon the human body.

5. Apparatus of the type described, comprising a plurality of electrode circuits for treating different parts of the body, a low frequency circuit adapted to be fed by a source of commercial alternating current, a high frequency circuit suitably connected 30 to be excited from said low frequency circuit, a plurality of independently adjustable regulating means for periodical actuation of the said circuits, and a switching mechanism 35 adapted to be operated in unison with said regulating means for alternate connection of said electrode circuits with said high frequency circuit.

6. Apparatus of the type described, comprising a low frequency circuit adapted to be connected to a source of alternating current, 50 a plurality of means working alternatively, for periodically interrupting this circuit, regulating means or adjusting the times of action of the former means, a primary oscillatory circuit excited from said low frequency circuit, a secondary oscillatory circuit, coupled with the primary circuit, a plurality of pairs of electrodes, and a switching device running synchronously with said interrupting means connecting the single pairs 55 of electrodes alternatively with said secondary oscillatory circuit.

7. In an apparatus for diathermic treatment the combination of a plurality of electrode circuits for treating different parts of 65 the body, a primary high frequency circuit, a secondary high frequency circuit coupled therewith, a plurality of independently adjustable regulating means for periodical actuation of the said circuits, and a switching mechanism adapted to be operated in unison 70 with said regulating means for alternate connection of said electrode circuits with said secondary circuit.

8. In an apparatus for diathermic treatment, the combination of a plurality of electrode circuits for treating different parts of the body, a high frequency secondary circuit, switching instrumentalities for periodically operatively connecting said high frequency 80 circuit in succession with said electrode circuits, and a feeding circuit including a plurality of current varying mechanisms, means for independently adjusting each of said mechanisms, and mechanical means for operating said switching instrumentalities and 85 said mechanisms in unison with each other.

In testimony whereof I have hereunto set my signature in the presence of two subscribing witnesses.

GUSTAV BUCKY.
